ROGER BIHLER, OF COLLEGE POINT, NEW YORK, ASSIGNOR TO MICHAEL A. BELKOFF, OF COLLEGE POINT, NEW YORK, AND ALLEN A. SLADE, OF RYE, NEW YORK

POWDER PUFF AND METHOD OF MAKING THE SAME

Original application filed June 23, 1930, Serial No. 463,007. Divided and this application filed June 4, 1931. Serial No. 543,020.

This invention relates to multi-ply enclosed articles, particularly powder puffs, and to a method for manufacturing the same.

In manufacturing powder puffs, a plurality of circular plies of plush or velour fabric are superposed face to face or nap to nap, and stitched for most of their periphery. Special machines have been devised to facilitate this stitching operation in an attempt to make it possible to manufacture powder puffs by quantity production methods, and such a machine is disclosed in my copending application Serial No. 128,885, filed August 12, 1926.

The pouch thus formed is inverted or turned inside out so as to bring the plush or velour surface outermost, after which the puff may be stuffed with a suitable soft filling, if desired. The opening which remains is then stitched by hand.

The primary and general object of the present invention is to provide a powder puff which is united entirely around its periphery with machine stitching; and further resides in the provision of a method for making such a powder puff, so that powder puffs may be made entirely by quantity production methods with relatively unskilled help.

The present application is a division of my copending parent application Ser. No. 463,007, filed June 23, 1930. The said parent application discloses the powder puff and method for making the same, and further discloses a novel powder puff sewing machine for performing the method. The claims of the said parent application are more particularly directed to the apparatus or sewing machine, while the claims of the present application are directed to the powder puff and the method of making the same.

When the opening in a powder puff, after turning the same, is closed, it is desirable that the fabric be turned inward and held together by a concealed stitch, so that the portion of the periphery which is sewed after turning will not be obviously distinguishable from any other portion of the periphery. It is also desirable that the stitching employed be sufficiently open and spaced to prevent the periphery from becoming hard and knotty, so that the entire puff including the periphery

thereof will be soft and velvety to the touch. These facts have encouraged the survival of hand methods for closing the puff, because in that method a peculiar stitch may be taken which turns the fabric inwardly and conceals the stitch, holding the same together. However, this stitch is tedious and time-consuming to make.

Accordingly, it is another object of the present invention to provide a machine stitched powder puff in which the stitching will be invisible, or if preliminarily visible will be of such a nature that it may subsequently be drawn taut and thereby concealed; and another object of my invention is to provide a method for so stitching the opening in turned powder puffs.

Many powder puffs are provided with a ribbon which extends diametrically across the puff. Such a ribbon is commonly provided by placing the ribbon between the superposed circular plies of material when the same are first stitched, the said stitching passing through and attaching one end of the ribbon. The puff is then turned, thereby not only bringing the soft faces of the fabric outermost, but also bringing the ribbon on the outside. In accordance with prior methods, the free end of the ribbon was tucked into the opening and attached to the puff when the opening was hand sewed. Further objects of the present invention are to attach such ribbon to the puff by machine stitching, and to provide a method for this purpose.

To the accomplishment of the foregoing and such other objects as will hereinafter appear, my invention consists in the powder puff and method of making the same as herein-after are more particularly described in the specification and sought to be defined in the claims. The specification is accompanied by a drawing in which:

Fig. 1 illustrates the first step in the manufacture of a powder puff;

Fig. 2 shows the same after turning;

Fig. 3 illustrates the preliminarily exposed stitching which closes the opening;

Fig. 4 is an enlarged section taken in the plane of the line 4-4 in Fig. 3;

Fig. 5 illustrates the finished puff after the

stitching has been drawn taut and the ribbon reversed;

Fig. 6 is an enlarged section taken in the plane of the line 6—6 in Fig. 5; and

Fig. 7 is explanatory of the stitch employed.

My improved powder puff and method for making the same may best be described with reference to Figs. 1 through 7 of the drawing. While the invention is generally applicable to enclosed multi-ply articles, it is particularly important and is here described in connection with the manufacture of powder puffs. For this purpose, a suitable soft fabric such as plush or velour is cut to circular configuration so as to form a plurality of discs of material the size of which depends upon the size of puff intended to be manufactured.

20 A pair of plies are then superposed in face to face relation, that is, with their soft sides or naps innermost, as is indicated by the plies 2 and 4 in Fig. 1 of the drawing. This assembly is then stitched for most of its periphery with a circular line of stitching 6 extending from the points 8 to 10 and leaving an unstitched opening 12. This stitching operation may obviously be done with a sewing machine instead of by hand, and in order 25 to make possible the rapid production of puffs which are truly circular and accurate in size, special powder puff sewing machines have been devised for this stitching operation. Such a machine is disclosed and 30 claimed in my prior copending application Ser. No. 128,885 previously mentioned.

The pouch thus formed is next inverted or turned inside out so as to bring the finished surface of the plies of material 2 and 4 outermost and also to enclose and conceal the line 40 of stitching 6. The puff then takes the form shown in Fig. 2 which contains the opening 12. If desired, suitable soft filling material may be placed within the puff through this 45 opening, after which the opening must be closed. This has heretofore been done by hand with a peculiar stitch which it is impossible to duplicate by machine and which serves to draw or tuck the edges of the material at the opening inward so that the resulting 50 peripheral portion of the puff is not conspicuously distinguishable from the machine sewed periphery of the puff. This hand sewing process is tedious and slow, relative to 55 machine methods, and does not result in perfectly uniform results, for the portion of the periphery which is sewed by hand seldom takes a truly arcuate shape of proper size to result in a perfectly round finished puff.

60 In accordance with the present invention, the opening is closed by a novel staggered stitch employing upper and lower threads which are looped together in a manner which is readily accomplished by machine. This 65 stitch is clearly shown in Fig. 7 and com-

prises an upper thread 14 and a lower thread 16 which are looped together outside of the puff, as at the loop 18, in such a manner that tension subsequently applied to the ends 20 and 22 of the threads pulls the threads taut 70 and tends to draw the material of the plies 2 and 4 of the puff over the stitch so as to conceal the same. Considering the stitch more in detail, it will be observed that the upper thread 14 and lower thread 16 are alternately looped inside of the puff, as at 24, and outside of the puff, as at 18.

This stitch is essentially a machine stitch, and its formation may best be and is in my copending parent application described in 80 connection with the sewing machine of my invention which makes the same, but it may briefly be stated at this point that the edges of the plies of material 2 and 4 are preliminarily bent inward at the opening, and that 85 the upper thread 14 is passed downwardly through the material of the puff and looped with the lower thread 16 to form a loop 24 inside of the puff, after which the upper thread 14 is passed downwardly outside of 90 the periphery of the puff and looped with the lower thread 16 to form a loop 18 outside of the puff, after which the upper thread 14 is again passed downwardly through the material of the puff and looped with the lower 95 thread 16 to form another loop 24 inside of the puff, and so on. Between the taking of each of these stitches, and preferably when the needle is retracted from the puff, the material at the opening may be pushed inwardly.

The puff is then in the condition illustrated in Fig. 3 and is closed, but in a relatively loose manner, with the external loops 18 of the stitching exposed. The condition of the 105 puff at this time is also clearly indicated in Fig. 4. At this point, the material of the puff at the opening may be again pushed inwardly to insure that the edges will remain in the desired inwardly bent relation, which incidentally loosens the loops of stitching. In accordance with my method, the ends 20 and 22 of the threads 14 and 16 are next drawn taut, and this takes up the slack in the loops 110 of thread and tends to draw the material 115 at the edge of the puff over the stitching, as is best indicated in Fig. 6. The opening is thus held closed by a staggered line of stitching which is located entirely inside of the puff, or which may be left slightly exposed, according to the tension placed upon the 120 threads before trimming the same from the puff.

If the puff is to be provided with a ribbon, an appropriate strip of ribbon 30 is placed 125 between the plies 2 and 4 of material when the puff is first stitched. The points 8 and 10, determining the line of stitching 6 and the opening 12 therebetween, are located at either side of one end of the ribbon 30, 130

the other end of the ribbon being attached by the line of stitching 6. The puff is then turned, and the turning operation is actually facilitated by the ribbon 30 which comes outside of the turned puff and is stretched diametrically over one of the faces of the same, as is shown in Fig. 2.

In accordance with the present invention, if the ribbon 30 has a right side and a wrong side, it is first placed over the puff with the wrong side uppermost. The end of the ribbon is tucked into the opening when the material at the edges of the opening is folded inwardly, and the puff is machine stitched with the 15 stitch previously described exactly as if the ribbon were not present, the stitching passing through the ribbon just as it passed through the material of the puff, as is evident from Fig. 3. When the ends 20 and 22 of thread 20 are drawn taut and trimmed from the puff, some of the external loops of stitching may remain somewhat exposed, particularly at the end of the ribbon, because the surface of the ribbon is not soft like the surface 25 of the puff itself. However, the ribbon is then turned to the opposite side of the puff, as shown in Fig. 5, or in other words, is turned upon that side of the puff which causes the end of the ribbon to conceal rather than expose the stitching attaching the same to the puff. If the ribbon has a wrong and a right 30 side, the better side is then brought outermost as it should be.

A preferred form of sewing machine for 35 practicing the foregoing method is described in my aforesaid parent application Ser. No. 463,007. The said machine comprises, generally, stitching mechanism, feed mechanism, pusher mechanism, and automatic stopping 40 mechanism which need not be described in detail here. The stitching mechanism includes a needle with an upper thread, and a shuttle carrying a lower thread. The needle is not only reciprocated longitudinally, 45 but is also reciprocated transversely, so that alternate stitches will be taken through the material of the puff and outside the periphery of the puff, as previously described. The shuttle is so designed that it loops the thread 50 carried by the needle in either the inward or outward positions of the needle. The feed mechanism includes a lower disc or table which is mechanically rotated preferably 55 intermittently by appropriate drive mechanism, and an upper disc urged downwardly for holding the work against the said table. If desired, a plurality of special powder puff 60 holders may be used, each of which receives an already turned and stuffed powder puff 65 and is placed with the powder puff in the machine for the sewing operation. Fixed guides and a mechanically reciprocated pusher finger are used in cooperation for bending the fabric of the puff inward during the sewing operation so as to insure that alternate

stitches do and do not penetrate the material of the puff. Automatic means may also be provided for stopping the sewing operation when the end of the opening in the puff is 70 reached.

In manufacturing the puffs one set of operators may perform the machine stitching operation indicated in Fig. 1 of the drawing. Another set of employees may turn the puffs and stuff the same. If holders are employed, 75 another set of employees may mount the turned puffs in the holders and preliminarily bend the edges of the opening slightly inward. The operators of the above-mentioned machines simply place the holder and puff in the machine and stitch the opening. Still another set of workers may, if necessary, again push the material at the opening inward and then draw the ends of the thread 80 taut and trim the same. If a ribbon is used on the puff, this ribbon is preferably reversed, as was previously described. The puff is then finished and may be packed for shipment.

It is believed that my novel powder puff, 90 which is machine stitched entirely around its periphery, and the method for making the same, and the many advantages thereof, will all be apparent from the foregoing detailed description. The opening in the stitched and turned puff is machine stitched with a stitch which, although initially externally exposed, 95 is so arranged that when drawn taut, it tends to draw the cloth of the puff around in a manner which conceals the stitch. This may be accomplished with a pair of threads looped together, by means of a needle and shuttle in a conventional manner, except that only alternate stitches are taken within the puff. The material at the opening in the puff is 100 constantly pushed inward and shaped to proper size during the stitching operation. The method may be employed even when the puff is provided with a ribbon which must be sewed to the puff when the opening therein 105 is closed.

It will be apparent that while I have shown and described my invention in the preferred form, many changes and modifications 110 may be made in the method and structure disclosed without departing from the spirit of the invention, defined in the following claims.

I claim:

1. A turned powder puff comprising inverted plies of material united entirely around the peripheries thereof with machine stitching.
2. A turned powder puff comprising inverted plies of material united entirely around the peripheries thereof with separate upper and lower threads machine stitched together.
3. A powder puff comprising a plurality of plies of material which are stitched together around most of their periphery with a

stitched and turned seam, while the balance of their periphery is stitched with separate upper and lower threads looped together.

4. A powder puff comprising a plurality of plies of material which are stitched together around most of their periphery with a stitched and turned seam, while the balance of their periphery is stitched with threads looped outside of the puff.

16. 5. A powder puff comprising a plurality of plies of material which are stitched together around most of their periphery with a stitched and turned seam, while the balance of their periphery is stitched with two threads, one passing through the upper and the other passing through the lower ply of material, said threads being alternately looped within the puff and without the puff.

20. 6. A powder puff comprising a plurality of plies of material which are stitched together around most of their periphery with a stitched and turned seam, while the balance of their periphery is stitched with two threads, one passing through the upper and 25 the other passing through the lower ply of material, said threads being so looped outside of the puff that tension on the ends of the threads tends to draw the material of the puff over the stitch.

30. 7. A powder puff comprising a plurality of plies of material and a ribbon, said plies of material being stitched together for most of their periphery with a stitched and turned seam including one end of the ribbon, while 35 the balance of the periphery and the other end of the ribbon are stitched with threads looped outside of the puff, said ribbon extending over that side of the puff which causes the ribbon to cover the exposed looped threads.

40. 8. A powder puff comprising a plurality of plies of material and a ribbon, said plies of material being stitched together for most of their periphery with a stitched and turned seam including one end of the ribbon, while 45 the balance of the periphery and the other end of the ribbon are stitched with two threads, one passing through the upper and the other passing through the lower ply of material, said threads being alternately looped within the puff and without the puff, and said ribbon extending over that side of the puff which causes the ribbon to cover the exposed looped threads.

50. 9. A powder puff comprising a plurality of plies of material and a ribbon, said plies of material being stitched together for most of their periphery with a stitched and turned seam including one end of the ribbon, while 55 the balance of the periphery and the other end of the ribbon are stitched with two threads, one passing through the upper and the other passing through the lower ply of material, said threads being so looped outside of the puff that tension on the ends of the

threads tends to draw the material of the puff over the stitching.

10. In the manufacture of powder puffs, the method which includes superposing plies of material, machine stitching the plies of material together for most of their periphery, turning the puff, and bending the open edges of the plies of material inward and machine stitching the same together.

11. In the manufacture of powder puffs, 75 the method which includes superposing plies of material, machine stitching the plies of material together for most of their periphery, turning the puff, bending the open edges of the plies of material inward and machine stitching the same together, and pulling the threads of the machine stitching taut.

12. In the manufacture of powder puffs, 80 the method which includes superposing plies of material, machine stitching the plies of material together for most of their periphery, turning the puff to bring the right side of the material outermost and to conceal the seam, filling the puff, bending the open edges of the plies of material inward, machine stitching the opening with a preliminarily exposed stitch, and pulling the threads of the machine stitching taut in order to conceal the same.

13. In the manufacture of powder puffs, 85 the method of stitching the opening left therein after turning the same, which includes bending the plies of material inwardly at the opening, machine stitching the opening, and pushing the material of the puff inwardly between the taking of successive stitches.

14. In the manufacture of powder puffs, the method of stitching the opening left 100 therein after turning the same, which includes bending the plies of material inwardly at the opening, alternately looping upper and lower threads and pushing the material of the opening inwardly, and pulling the threads taut.

15. In the manufacture of powder puffs, the method of stitching the opening left 105 therein after turning the same, which includes bending the plies of material inwardly at the opening, passing an upper thread downwardly through the material and looping it with a lower thread, passing the upper thread downwardly outside of the periphery of the puff and looping it with the lower thread, again passing the upper thread downwardly through the material of the puff and looping it with the lower thread, and so on.

16. In the manufacture of powder puffs, 115 the method of stitching the opening left therein after turning the same, which includes bending the plies of material inwardly at the opening, machine stitching the opening by passing an upper thread downwardly through the material and looping it with a 120

lower thread, pushing the material inwardly, passing the upper thread downwardly outside of the periphery of the puff and looping it with the lower thread, pushing the material inwardly, again passing the upper thread downwardly through the material of the puff and looping it with the lower thread, and so on, and pulling the ends of the pair of threads in order to tighten the loops and conceal the same.

10 17. In the manufacture of powder puffs, the method which includes superposing a pair of plies of material with a ribbon therebetween, machine stitching the plies of material for most of their periphery and including one end of the ribbon, turning the material to conceal the seam and to bring the ribbon outside, machine stitching the opening in the puff and the other end of the ribbon with an exposed stitch, and turning the ribbon to the opposite side of the puff in order to conceal the exposed stitch.

15 18. In the manufacture of powder puffs, the method which includes superposing plies of material with a ribbon therebetween, machine stitching the plies of material together for most of their periphery and including one end of the ribbon, turning the puff, machine stitching the opening and the ribbon and meanwhile pushing the material of the puff inwardly between the taking of successive stitches, and finally turning the ribbon to the other side of the puff.

20 19. In the manufacture of powder puffs, the method which includes superposing plies of material with a ribbon therebetween, machine stitching the plies of material together for most of their periphery and including one end of the ribbon, turning the puff, bending the open edges of the plies of material and the other end of the ribbon inwardly, machine stitching the opening and the ribbon by passing an upper thread downwardly through the material and looping it with a lower thread, pushing the material inwardly, passing the upper thread downwardly outside of the periphery of the puff and looping it with the lower thread, pushing the material inwardly, again passing the upper thread downwardly through the material of the puff and looping it with the lower thread, and so on, pulling the threads taut, and turning the ribbon to the other side of the puff.

25 Signed at College Point in the county of
Queens and State of New York this 27th day
of May, A. D. 1931.

ROGER BIHLER.
